UNITED STATES PATENT OFFICE.

FINLEY MCARTHUR, OF CEDAR RAPIDS, IOWA.

WATERING DEVICE.

1,413,675.

Specification of Letters Patent. Patented Apr. 25, 1922.

Application filed May 17, 1920. Serial No. 382,051.

To all whom it may concern:

Be it known that I, FINLEY MCARTHUR, a subject of the King of Great Britain, and a resident of Cedar Rapids, Linn County, 5 Iowa, have invented certain new and useful Improvements in Watering Devices, of which the following is a specification.

My invention relates to improvements in watering devices for stock, and the objects 10 of my improvements, are to provide for a relatively large inlet-opening or man-hole for a water-supplying tank water-sealing means for said opening when it is closed to furnish a manually controllable closure for 15 the delivery-port of the tank, and otherwise to improve the structures and uses of such a device, in ways which will be hereinafter more fully described and pointed out in the claim, and which are illustrated in the accompanying drawings.

In said drawings, Fig. 1 is a vertical medial longitudinal section of said water-supply tank, its enclosure, and other auxiliary structures, and as shown along the broken 25 line 1—1 of Fig. 2, while Fig. 2 is a vertical transverse section of the device taken on the broken line 2—2 of said Fig. 1, looking in the direction indicated by the arrow.

The water-supply tank 1 may be of any 30 desired shape, but is shown as a horizontally positioned cylinder, having near one end of its top an upwardly-rimmed inlet or man-hole 2, and in the middle of its bottom a downwardly-rimmed and relatively restricted outlet 7. An upwardly-flanged annulus 3 is hermetically and concentrically positioned about and spaced from the raised rim 2, both being approximately of the same height, supplying an annular trough between them. The numeral 4 denotes an imperforate closure for said inlet-opening, in the shape of a discoidal plate having an annular depending marginal rim, the latter being of a diameter midway in dimension 45 between the diameters of the rims 2 and 3, whereby the rim of said closure 4 may depend into the trough between the rims 2 and 3.

When the tank has been filled with water 50 through said inlet the closure is fitted thereto as shown in said Fig. 1, by means of its bail or handle 5, and water is poured into said trough, thus sealing the joint.

The tank 1 is removably supported upon 55 a pair of downwardly-bowed transverse bars 12. The ends of the bars 12 are sup-

ported upon blocks 13 fixed on adjacent supporting structures, which may be the inner walls of a casing or enclosure 29, the latter being roofed over, with a large opening left 60 in the roof immediately above the inlet of the tank. This roof opening may be closed by a longitudinally sliding cover 32. The said enclosure 29 may have a closed bottom 37, and along opposite inner longitudinal 65 walls of the enclosure inwardly-beveled blocks 17 may be mounted, spaced apart, to support opposite parts of the bottom of a removable drinking-trough or vessel 28, whose sides and ends are inclined in a well-known manner. In one end-wall of said enclosure is a door-opening 19 closed by an upwardly-sliding door 20, the latter having a vertical slot 21 to receive a bolt 23 which traverses said end-wall, and the door may be 70 secured in an adjusted lifted position by means of a wing-nut on said bolt, as shown at 22.

In the middle of both side-walls of the enclosure are like door-openings 15 which are 80 closed by depending doors 14 hinged at the top, the doors being located within the enclosure to be swung open inwardly by pressure thereagainst from without as by an animal's nose. Either opening 15 also serves 85 the purpose of insertion of the trough 28, or its withdrawal. When the trough is inserted into the enclosure slopingly, its advancing sloped end-wall may easily ride up the slope or bevel 18 of the block 17 ahead, 90 in order to come to position horizontally upon the blocks without interference with other abutting structures, and of course, in the act of a removal, the reverse actions are had.

As thus positioned on the blocks 17, the trough is immediately below the delivery-outlet nipple 7 which delivers thereto. In order to close this outlet while the tank 1 is being filled, I have supplied a swinging 100 closure, consisting of an arm 9, preferably weighted as shown, one end of which is pivoted at 10 to spaced depending lugs 11 fixed on the bottom of the tank. The opposite or free extremity of said arm has an eye to receive one end of a pull-cord 24, the latter being reeved over small sheaves 25 and 26 on the bottom of the tank, and carried thence upwardly and provided on its upper end with a ring which may be slipped over a 110 hook 27 in the wall of the enclosure. When so hooked up, the arm 9 is swung up caus-

ing its domical boss to close the nipple 7. When the cord is released from said hook, the gravity of the weighted arm swings it to lowered and open position, so that water 5 may freely issue into the trough.

In the upper part of the enclosure 29 is an air-vent 30 to release gases of combustion in a draft from a lamp 33 placed in the enclosure under and to warm the contents of 10 the tank. I have positioned a removable tube 6, with open ends, within and fitting the upper part of the nipple 7, and which extends upwardly into the tank far enough to retain a small quantity of water over the 15 bottom of the tank, to prevent injury to the tank by overheating.

Stock can easily push in the swinging doors 14 in order to insert their heads to drink from the trough, the doors swinging 20 back to close the door openings, by their own gravity. To hold the trough from being pushed off said blocks, one end passes under a hook 16, while the other end is 25 releasably retained by a swinging hook 35, pivoted at 34 without the door between lugs 33. The lugs are orificed in line to receive a fastening-pin 36, to hold the hook clamped upon the trough, releasably.

Having described my invention, what I claim as new, and desire to secure by Letters Patent, is:

In a device of the character described, a closed housing having an opening in its top, a sliding closure for said opening, a drinking-vessel seated removably in the lower 35 part of the housing, a tank supported removably in the housing above and spaced from said vessel and having a delivery-vent above the vessel with nipple extending thereinto, a movable closure for said vent, said 40 tank having an inlet-opening in its top, a removable closure for said inlet-opening, door-openings in opposite side-walls of said housing adjacent opposite ends of said drinking-vessel, movable closures for said door-openings adapted to be propelled inwardly under pressure of an animal's nose, a fixed hook releasably engaging one end of said drinking-vessel, and a swinging hook engaging the 45 opposite end of said vessel releasably, and 50 releasable means for locking the latter hook in its engagement with said vessel.

Signed at Waterloo, Iowa, this 14th day of May, 1920.

FINLEY McARTHUR.
